(57) **CLAIM**

The ornamental design for an in-footwear lace tightening reel, as shown and described.

DESCRIPTION

FIG. 1 is a left side view of a first embodiment of an in-footwear lace tightening reel showing my new design; FIG. 2 is a front view thereof; FIG. 3 is a top view thereof; FIG. 4 is a right side view thereof; FIG. 5 is a rear view thereof; FIG. 6 is a bottom view thereof; FIG. 7 is a left side view of a second embodiment of an in-footwear lace tightening reel showing my new design; FIG. 8 is a front view thereof; FIG. 9 is a top view thereof; FIG. 10 is a right side view thereof; FIG. 11 is a rear view thereof; and, FIG. 12 is a bottom view thereof. The broken lines shown in the drawings represent portions of the in-footwear lace tightening reel that form no part of the claimed design.

1 Claim, 12 Drawing Sheets
